PAPER PULP REFINER

Joseph E. Bond, Middletown, Ohio

Application August 26, 1936, Serial No. 97,958

1 Claim. (Cl. 92—26)

This invention relates to refining apparatus for paper pulp and the like.

One object of the invention is the provision of a refining apparatus for beating and treating paper pulp and other similar or related substances, adapted to produce a refined defibering action with a comparatively small power consumption and capable of treating an unusually large amount of pulp or other fibrous material in a comparatively short time.

Another object of the invention is the provision of a refining unit of the character mentioned, having a comparatively few outer or bed units that are adjustably movable in a radial direction towards and away from a rotatable plug member or rotor, the rotor and the casing in which the bed units are supported having refining bars which treat the pulp in a uniform manner as the pulp travels from one end of the casing to the other along the outer side of the rotor.

Another object of the invention is the provision of a refining apparatus having several radially adjustable bed members each of large size and guided in the casing in such a manner as to avoid objectionable vibration and noise.

Another object of the invention is the provision of a refining apparatus of the character mentioned, in which the bed units extend through a comparatively large part of the periphery of the casing, the bed units including bar supporting metal holders that have extended guiding surfaces large enough in radial direction to effectively prevent vibration during operation.

Another object of the invention is the provision of a refining apparatus especially adapted for repeated circulation of the paper pulp from one end of the apparatus to the other end and capable of treating the paper pulp with very little cutting action and with considerable hydration and in an exceedingly efficient and rapid manner.

Another object of the invention is the provision of a paper pulp refining apparatus having radially adjustable bed members which are automatically adjusted to proper clearance position with respect to the rotor bars in accordance with the power consumption of the drive motor.

Another object of the invention is the provision of a paper pulp refining apparatus having bars which are made from basal lava or the like and adapted to handle pulp stock of a consistency of 8% or 10% or more.

Other objects and advantages of the invention will be apparent from the following description, the appended claim and the accompanying drawings, in which—

Fig. 1 is a diagrammatic illustration of a pulp-
ing system embodying the present invention,
drawn on a small scale;

Fig. 2 is a longitudinal sectional view on line
2—2 of Figs. 1 and 3 through a portion of the
pulping system, showing the refining unit in cen-
tral vertical section;

Fig. 3 is a vertical section taken on the line
3—3 of Fig. 2;

Fig. 4 is a perspective view of the refining unit; 10

Fig. 5 is a perspective view of a portion of the
refining unit rotor having straight refining bars,
and an associated bed unit;

Fig. 6 is a perspective view of a rotor in which
the bars are arranged at a substantial helical 15
angle, and an associated bed unit;

Fig. 7 is a diagrammatic view showing the
electrical control of the adjusting motors which
regulate the position of the bed units.

Referring more particularly to the drawings by 20
reference numerals, Fig. 1 illustrates an appara-
tus in accordance with the invention in which
paper pulp or other fibrous material is broken up,
pulped and refined. The system comprises a cir-
culating tank 10 to which pulp laps or other ma-
terial to be pulped and defibered is introduced,
this material flowing around midfeather 11 and 25
into the inlet passage 12 of a disintegrating ap-
paratus designated generally by the reference nu-
meral 13. The disintegrating apparatus, which
is shown more in detail at the left-hand end of 30
Fig. 2, comprises a series of high-speed rotating
disintegrating blades 14 which are adapted to
beat, whirl, and shred the stock pieces and to
perform an effective disintegrating action as the 35
pulp pieces pass along to the outlet 15 of the dis-
integrating apparatus. The pulp is forced along
by the action of the disintegrating blades 14
which have a propelling effect and by propelling
or pumping blades 16. The pulp is thus forced 40
along to the passage 17 which extends upwardly
and through which the stock is returned back
through the return passage 18 to the circulating
tank 10, the stock then returning in the tank by
gravity, to repeat the circuit. 45

Some of the stock that has been pulped and
disintegrated and which is supplied to the passage
17 is forced, as by means of propelling blades 19
on the same high speed rotary shaft 19a that
carries the disintegrating blades 14, to the inlet 50
passage 20 of the refining apparatus which is
designated generally by the reference numeral 21.
The stock is given a refining action as it passes
through this apparatus to the outlet passage 22,
which preferably returns some of the stock to 55

the circulating tank 10 although a portion of the refined stock may be withdrawn as desired and supplied to the flow box of the paper machines or to any point of use. As will be understood, it is intended that the stock shall repeatedly circulate through the refining apparatus so that its refining action can be performed a number of times on any stock particle before the stock is supplied to a point of use.

- 10 The refining apparatus 21 as will be more apparent from Figs. 2, 3 and 4, is one that is adapted for a refining action which is substantially uniform in character as the stock passes from one end of the apparatus to the other, the passage of the stock taking place at a substantially constant distance from the axis of rotation and thus having a uniform skin friction loss and a uniform bar-pass-treatment as it passes from the inlet 20 to the outlet passage 22. It has been found that the speed of movement of a refining bar and the number of bar passes per minute determine, to some extent, the particular treatment to which the pulp is subjected, and the particular results obtained. In a device in which the plug is tapered, as in the usual Jordan engine construction, the peripheral speed of the bar at the small end of the plug will be very much less than the peripheral speed at the larger end of the plug and the bar passes per minute will be quite different at different ends of the Jordan. The pulp in a Jordan engine will thus be subjected to different kinds of refining actions as it passes once through the jordan. In accordance with the present invention, however, the proper speed of operation can be determined and selected in accordance with the desired characteristics of the pulp so that the pulp will be effectively treated in the proper manner and most effectively for any particular stock requirement, and the power will thus be most effectively utilized in the refining action that is produced. It is also desirable that the same refining apparatus be capable of treating the stock fibers differently as desired. In accordance with the present invention the machine can give a gentle but effective and continued brushing action under considerable pressure head without much chopping or cutting action on the stock fibers, so that the fibers are long and are hydrated effectively to produce a strong tough sheet. By decreasing the speed of operation, changing the operating clearance of the bars, and decreasing the pressure head and the stock consistency the treatment of the stock can be such as to give increased chopping action and a bulky soft sheet.
- As will be apparent, in accordance with applicant's invention, the number of passes that any rotor bar makes with respect to the fixed bars at one end of the apparatus will be the same as the number of passes made in any given time at the other end of the apparatus, and it is the number of passes in any given unit of time which to a large extent determines the effectiveness of the refining action.
- 65 More particularly, the refining apparatus comprises a casing or housing 24 in which the rotor 25 is rotatably mounted as by means of a suitable bearing 26 at one end of the shaft 19a, the other end of the shaft being supported by bearing 27 which is mounted on the common supporting base 28 of the refining apparatus.

The rotor 25 comprises a number of bars 30 which extend from one end of the rotor to the other and which are spaced apart so as to provide passages or channels 31 between adjacent

bars. The bars are preferably of substantial width and may be straight so as to extend parallel to the axis of rotation, as illustrated in Fig. 5, or may be arranged helically at a substantially helical angle, as in Fig. 6, as desired for the particular treatment to be given to the pulp. As herein shown, the bars 30 are made from a basalt lava or the like, which is a stone of a porous character and which is adapted for a rather gentle refining action on paper pulp stock and the like. The bars 30, however, may be made of other suitable material especially where the cutting action is intended to be more severe, or where it is not desired to produce a comparatively high degree of hydration on the stock. The bars 30 are preferably cemented in place in sockets provided in the metal skeleton frame 32 which is fixed on the shaft 19a, the cement 33 rigidifying the structure and preventing outward movement of the bars and also permitting the bars to wear a considerable distance while maintaining the frame 32 well out of contact with any stationary part of the apparatus.

The bars 30 are adapted for cooperation with bed units 35 which are comparatively large in size and few in number and each of which comprises one or more bars, preferably of basalt lava to produce the desired refining and rolling action. Each bed unit may present a single continuous part-cylindrical surface so as to give the maximum surface of refining contact with the material treated although grooves 36 may be provided at a suitable angle in the basalt lava bed members so as to provide spaced bars 37 which are normally fixed and which are adapted for cooperation with the rotatable bars on the rotor which operate with a clearance of a few thousandths of an inch or with a clearance considerably greater or somewhat less than this, as desired for the particular refining action to be produced. The grooves 36, as shown in Fig. 5, extend helically at a substantial angle from a point adjacent the inlet passage at one end of the casing to the other end of the casing.

The bed units 35, 35a and 35b are adapted to be adjusted radially towards or away from the axis of rotation of the rotor to vary the clearance between the rotor bars and the bed units. As will be more apparent from Fig. 3, each of the bed units 35, 35a and 35b is secured in a holder 38, being attached rigidly to the same by cement 39. The holder 38 is a metal member, preferably of cast iron, and having extended guide surfaces 40 of comparatively large radial extent, and reaching from one end of the bed unit to the other. The length of the guide surfaces measured in a substantially radial direction is about the same as the rotor radius in the embodiment shown, so that vibrational movements, during operation, are prevented. The ends of the holder are also guided for sliding movement in the casing 24, which is also preferably a metal casting and which is preferably provided with a clearance adjusting block or shim 41 for each bed unit, adjustable by means of positioning screws 42 so that any play or looseness such as might produce vibration can be readily taken up. Each bed unit extends throughout a very large proportion of the annular extent of the casing, only a few of such bed units being employed so that each will extend through not substantially less than 90° of the complete circular extent of the casing. Each unit will thus be of quite large size, and inasmuch as there is a very large effective area guiding the bed unit in the casing, 75

objectionable vibration of the bed units and their parts will be avoided during operation. A comparatively large number of bed units inadequately supported in the casing would vibrate objectionably, the vibration rapidly producing wear as well as noise and causing objections that are avoided by the present invention.

It is preferred that only three bed units will be employed, one of the bed units being arranged centrally at the upper portion of the machine and the other two bed units being symmetrically arranged 120° apart so that the total height of the machine can be kept within desirable limits, and so as to provide an equalized and symmetrical construction and one in which there is no objectionable vibration.

The bed units are adapted to be adjusted mechanically and in a positive manner so that their positions with respect to the axis of rotation can be changed simultaneously equally and exactly to any desired extent. Thus the bed unit 35 shown at the top of Fig. 3 is positioned at one end by means of a rotatable shaft 46, the lower end of which is rotatably mounted in the bed plate holder 38, although relative axial movements of these parts is prevented. The upper portion of the shaft 46 is threaded as indicated at 47 and the threads are engaged by a rotatable nut 48 which is supported for rotational movements at a fixed distance from the shaft 19a, being mounted on the head portion 49 of the casing 24. As will be understood, rotational movements of the nut 48 moves the shaft 46 axially, and thus varies the position of the bed unit with respect to the center of the shaft 19a in order to change the clearance between the rotor bars and the fixed bed bars. The nut 48 is fixed to a worm gear 50 which is rotated by means of a worm 51 provided on a shaft 52, the latter being operated by a suitable reversible electric motor 53. The electric motor 53 can be controlled so as to move the screw 46 either inwardly or outwardly as desired.

As will be apparent from Fig. 2, the supporting and adjusting means just described for one end of the bed unit is duplicated adjacent the other end of the bed unit, the two screws 46 being simultaneously rotated by means of a common shaft 52 under the control of the driving motor 53. As shown in Fig. 2 a suitable manually controlled handwheel 55 may be supplied on the shaft 52 if desired.

The bed units 35a and 35b which are provided in the lower portion of the machine are arranged and supported for adjustment, etc., in a manner similar to the bed unit 35 as above described. The bed unit 35a is adapted to be controlled directly by the electric motor 53a while electric motor 53b controls the movements of the bed unit 35b. However, the three motors 53, 53a and 53b are preferably interconnected mechanically by means of sprocket gears 57 and a common sprocket chain 58 so that the three bed units are compelled to move the same distances inwardly or outwardly and thus maintain a uniform clearance with respect to the rotor bars. At the first operation of the apparatus the bed units may be adjusted to practically zero clearance so as to grind the bed bars and the rotor bars on one another to obtain a uniform height of the bars, and then the bed units are backed off to a proper operating clearance of a few thousandths of an inch.

The refining apparatus provided with a number of straight basalt lava bars on the rotor, and

with a comparatively few large sized bed units adapted for radial adjustment on the stationary casing provides a construction adapted for handling stock up to 4% or 5% consistency, or more, as stock of this consistency can pass from one end of the rotor to the other through the channels or passages 31 which are provided between adjacent bed units and can be caused to pass from one end of the apparatus to the other.

With the bars on the rotor comparatively few in number and with considerable spaces between the bars, and with the bars on the rotor and the bars on the bed units inclined helically and oppositely with respect to one another as in Fig. 6 so as to give a quite effective propelling action from the inlet to the outlet passages, the apparatus is such as to operate effectively on pulp stock up to about 12% consistency although stock of such high consistency cannot be pumped by the usual pump devices. In accordance with applicant's invention, however, the pumping action produced by the blades 19 coupled with the propelling action produced by reason of the angular sweep of the bars 30a of the rotor past the bars 37a of the bed units during operation is adequate to produce an effective movement of pulp stock through the apparatus. The stock can thus readily pass to positions between adjacent bars, and can then flow out into the effective treating range between the rotor bars and the stationary bars on the bed units as the rotor moves, thick stock being prevented from gathering in balls or lumps since the stock is passing continuously from between one pair of bars, into the space between stationary and fixed bars, and then to the space between some other pair of bars, during its axial travel. With the basalt lava bars on both the rotor and on the stationary bed units, a comparatively gentle refining action of the thick stock will take place and a large amount of hydration will be pronounced especially with high pressure head at the outlet passage of the apparatus.

With the bars on the rotor inclined helically and oppositely with respect to the bars on the bed units at a substantial angle as illustrated in Fig. 6, a construction is provided in which metallic substances that might find their way into the mass being treated will be forced along by the angularly intersecting surfaces of the fixed and rotatable members, without injuring the members even though they are of stone construction. The action is somewhat like that given to a metal object between the blades of a pair of scissors when the blades of the scissors are at an angle of 45° to 90° with respect to one another. This is of importance in a construction of this kind in which the bars of the rotor and of the stator are of stone construction that otherwise might be damaged very materially by metal objects such as a nut for example passing through the apparatus.

It will also be noted from Fig. 2 the disintegrating blades 14 and the pump blades 16 may be provided on the same shaft, 19a, that carries the rotor of the refining apparatus. Both ends of the refining apparatus are of comparatively large diameter, the outside diameter of all of the blades on the shaft being less than the inside diameter of the end wall of the refining apparatus which encloses the pumping blades 19. The entire shaft with its supported members thereon may therefore be withdrawn to the right from the shells or housings in which it is located.

With all of the stock receiving that particular

degree of refining action that is most desirable, since the stock passage is of a consistent diameter, and with the apparatus operating on thick stock and thus effectively defibering large quantities of fiber in any given time, it will be apparent that the power is most effectively utilized so that a great reduction in the amount of power required results.

Any proper speed of rotation of the rotor can be selected, under the manual control of the operator, and any variations of the speed of operation that may be desired can be obtained. It is preferred, however, that under normal conditions the adjustable bed units should be adjusted automatically to maintain an effective refining action and in order that the amount of effective work accomplished by the apparatus should be maintained substantially constant. With the skin friction remaining substantially constant at any given speed of rotation, as the pulping progresses it is desired to change the setting of the bed units so as to maintain the amount of work done by the apparatus at some value. The power consumption of the driving motor is a measure of the effectiveness of the refining or pulping action taking place.

For this purpose the three adjusting motors 53, 53a and 53b may be controlled by suitable reversing switch mechanism, designated generally 65, see Fig. 7, the reversing switches being energized from the three phase line 66 and controlled by suitable relay coils 67 and 67a. The relay coils are controlled automatically in such a way that when the load decreases on the main driving motor 69, which is fixed to the shaft 19a, the adjustable bed units are brought closer to the axis of rotation of the roll thus decreasing the clearance and increasing the amount of work. The main driving motor 69 is driven from the three-phase line 70 through a switch 71. The transformer primaries 72 and 73 are connected across two phases of the power supply and their respective secondaries 72a and 73a are connected as shown to a series of control switches including a manually operable switch 74 by means of which the load can be increased and a manually operable switch 75 by means of which the load can be decreased. Operation of these switches control the energization of the relays 67 and 67a in a selective manner and under manual control so that the setting of the bed units can be changed manually even before the main drive motor is started.

During operation, the current transformer secondary 76 in one line of the main driving motor supply automatically controls the amount of current flowing through a contact making ammeter 77 which controls a movable contact 78 and causes it to contact with either one of the primary coils

of the relays 67 and 67a depending on the amount of current flowing and thus depending on the amount of work done. A controllable rheostat 80 can be manually operated to change the load setting so that when it is intended that the load should be decreased, as for a desired increase of speed of rotation, then this can be effected manually by suitable control of this rheostat. It will be apparent, however, that during normal operation, the proper initial speed of operation having been determined for the particular character of treatment desired and the character of the stock treated, the rheostat 80 will be set so as to automatically maintain the defibering action at an effective rate, the bed members being adjusted automatically towards and away from the axis of rotation of the rotor to maintain the amount of work constant or substantially constant.

While the forms of apparatus herein described constitute preferred embodiments of the invention, it is to be understood that the invention is not limited to these precise forms of apparatus, and that changes may be made therein without departing from the scope of the invention which is defined in the appended claim.

What is claimed is:

A defibering apparatus for paper pulp and the like comprising a refiner having a casing provided with an inlet passage at one end and an outlet passage at the other end, said casing having several radially movable bed units slidably supported therein, a rotor operable in said casing and having a series of refining bars adapted for cooperation with said bed units, the outside diameter of said bars being substantially uniform from one end to the other of the rotor to provide a substantially uniform treatment for stock flowing from said inlet passage to said outlet passage, a supporting shaft on which said rotor is carried, pumping blades extending outwardly from said shaft, and a series of stock disintegrating blades extending outwardly from said shaft and arranged axially of said pumping blades, a housing for said blades and including a wall arranged around said pumping blades and at an end of the rotor between the stock disintegrating blades and the rotor, said housing surrounding said stock pumping blades and said wall having an opening of smaller diameter than the rotor but of larger diameter than all of said blades through which the blades while on said shaft can be withdrawn in an endwise direction, a circulating tank, and means connecting said tank to said housing and connecting said refiner to said tank for the continuous circulation of pulp through the refiner.

JOSEPH E. BOND.
